UNITED STATES PATENT OFFICE.

WILLIAM F. FARLEY AND THOMAS H. FARLEY, OF ELDORADO, OKLAHOMA.

GROCERY-CABINET.

1,030,172.

Specification of Letters Patent. Patented June 18, 1912.

Application filed February 26, 1912. Serial No. 679,912.

To all whom it may concern:

Be it known that we, WILLIAM F. FARLEY and THOMAS H. FARLEY, citizens of the United States, residing at Eldorado, in the 5 county of Jackson and State of Oklahoma, have invented new and useful Improvements in Grocery-Cabinets, of which the following is a specification.

Our invention pertains to cabinets; and it 10 has for its object to provide an inexpensive and neat cabinet constructed with a view to keeping separate and displaying produce of different kinds to advantage, and this in such manner that while the different kinds 15 of produce cannot be handled by prospective purchasers, the same can be expeditiously and easily removed from the cabinet when a sale is to be made.

The cabinet is designed more particularly 20 for use in a grocery store, and to contain beans, peas, rice, hominy and like products; and its novelty and practical utility will be fully understood from the following description and claims when the same are read 25 in connection with the drawings, accompanying and forming part of this specification, in which:

Figure 1 is a perspective illustrating a 30 cabinet constructed in accordance with our invention. Fig. 2 is an enlarged section taken through the transverse center of one of the bins or compartments of the cabinet. Fig. 3 is an enlarged detail section taken in 35 the plane indicated by the line 3—3 of Fig. 2 and showing the means for controlling the discharge of substance from each of the several compartments or bins of the cabinet.

Similar numerals of reference designate 40 corresponding parts in all of the views of the drawings.

The frame of our novel cabinet may be made of wood, metal or other material consonant with the purpose of the cabinet, and comprises a bottom 1, end walls 2, a lower 45 longitudinal front bar 3, an upper longitudinal front bar 4, spaced a considerable distance from the bar 3, a back wall 5, and flanges extending inward from the bar 4, the end walls 2 and the back wall 5. On the 50 bottom wall 1 is arranged the rear portion of a false bottom 6, which has its forward portion supported on a longitudinal cleat 7 fixed to the inner side of the front bar 3. By virtue of this arrangement, it will be 55 manifest that the false bottom 6 is inclined rearward and downward with a view to fa-

cilitating the passage of the beans, peas, etc., to the outlets hereinafter referred to.

In addition to the elements hereinbefore referred to, the frame of the cabinet comprises transverse partition walls 8, by which the cabinet is divided into a plurality of bins or compartments, one of which is shown in Fig. 2. The said partitions 8 are preferably made of wood, metal or other opaque material, but we would here have it distinctly understood that the said partitions are not necessarily of opaque material. On the other hand they might obviously be formed of glass or other transparent material, without involving departure from the scope of our claimed invention. The partitions 8 are fixed in workmanlike manner to the bottom and back walls of the frame, as well as to the false bottom 6, and extending 60 longitudinally above the said partitions and between the end walls 2 of the frame is an additional frame bar 9. This frame bar 9 serves in combination with end cleats 10, one of which is shown in Fig. 2, to support the 65 top glass panel 11 of the cabinet, and this in a horizontal plane below the top flanges of the upper front bar 4 and the back wall 5. In addition to the top glass panel 11, the 70 cabinet comprises a front glass panel 12, and consequently it will be manifest that the goods in the several bins or compartments will be displayed to advantage and can be conveniently and thoroughly inspected by prospective purchasers, and yet purchasers cannot handle and thereby bring 75 about deterioration of the goods.

Slidable forward in ways provided in the end walls 2 and from the flange of the back wall 5 is a lid 13 through the medium of 80 which the filling openings of the several bins or compartments are normally closed. The said lid is preferably provided with hand holds 14, and when it is moved forward to its open position it rests on the 85 glass panel 11 as shown in Fig. 2, and when it is closed it brings up against the flange of the back wall 5. By opening the said lid 13 any one or all of the bins or compartments may be expeditiously and easily filled to the 90 extent desired with the goods to be held and displayed.

Formed in the rear portion of the bottom wall 1, one to each bin or compartment, are outlet openings 15, which are preferably 100 tapered or gradually reduced in diameter 105 downward as shown in Figs. 2 and 3, and

formed in the underside of the bottom wall 1 and communicating with the openings 15 are guideways of which there is one for each bin or compartment. The side walls 5 of the said guideways are undercut or dovetailed, as indicated by 16 in Fig. 3, and in the said guideways are valve slides 17, of which there is one to each bin or compartment. The said valve slides are identical in 10 construction, and therefore a detailed description of the one shown in Figs. 2 and 3 will suffice to impart a definite understanding of all. It will be understood by reference to Fig. 3 that the longitudinal 15 edges of the slide 17 are beveled to conform to the undercut walls 16, and that the slide is provided with an opening 18, which is preferably tapered downward, and is also provided with a discharge funnel 19 in communication with said opening 18. Of course the openings in the bin bottoms and the valve slides may be varied in size according to the character of goods to be displayed in the cabinet, and it will also be 20 understood that when desired the openings complementary to some of the bins or compartments may be larger than the openings of the others.

When it is desired to take beans, peas, 30 rice or the like from a compartment and for delivery to a purchaser, the clerk standing at the back of the cabinet has but to hold the mouth of a bag about the spout 19 of the particular compartment, and then using 35 the said spout as a handle to draw the valve slide rearward until its opening 18 is in registration with the opening 15 in the bottom wall 1. When this is done, the substance in the bin or compartment will pass 40 freely through the registered openings and the spout and into the bag, and then when the bag is filled to the extent desired, the clerk by pressing forward on the spout 19 or by pressing forward with his body on 45 the rear end of the slide 17, can conveniently and effectually close the opening 15 and prevent the further discharge of substance from the bin or compartment. It will be further gathered from the foregoing that 50 when the lid 13 and the several valve slides 17 of our novel cabinet are closed, the goods contained in the several bins or compartments will be protected from dust, dirt and the like.

55 We have entered into a detailed description of the construction and relative arrangement of the parts comprised in the present and best practical embodiment of our invention of which we are cognizant, in 60 order to impart a full, clear and exact understanding of the said embodiment. We do not desire, however, to be understood

as confining ourselves to the said specific construction and relative arrangement of parts, as manifestly such modifications may 65 be made in the future practice of the invention as do not involve departure from the scope of our invention as claimed. For instance it is to be positively understood that the said discharge funnel 19 may be permanently attached to the bottom wall 1, or vice versa to the slide 17, preferably to the bottom wall 1.

Having described our invention, what we claim and desire to secure by Letters-Pat- 75 ent, is:

1. In a grocery cabinet, a bin comprising a back wall, and a bottom wall having an opening in its rear portion and a guideway formed in its underside and extending to 80 its back edge, a front transparent panel, a top transparent panel having its rear edge spaced from the back wall of the frame and arranged in a horizontal plane slightly below the upper edge of said back wall, a 85 false bottom inclined downward and backward from the front panel to a point adjacent the opening in the bottom wall, a closure lid slidable forward from the back wall and on the top panel, and a valve slide 90 arranged in the said guideway of the bottom wall and having an opening adapted to be placed in and out of registration with the opening in the bottom wall.

2. In a grocery cabinet, a plurality of 95 bins arranged in a unitary structure and side by side and having a common bottom wall provided with openings in its rear portion and also provided with guideways formed in its underside and extending to 100 its back edge and also having a common front transparent panel and a common top transparent panel and a common back wall; the rear edge of the top transparent panel being spaced from said back wall, partitions between the bins, a false bottom inclined downward and backward from the front panel to a point adjacent the openings in the bottom wall, a closure lid common to the several bins and slidable for 105 ward from the back wall and on the top transparent panel, and valve slides, one to each bin, arranged in the said guideways of the bottom wall and having openings adapted to be placed in and out of registration 110 with the openings in the bottom wall.

In testimony whereof we have hereunto set our hands in presence of two subscribing witnesses.

WILLIAM F. FARLEY.
THOMAS H. FARLEY.
